(57) **CLAIM**

The ornamental design for a display screen, as shown and described.

DESCRIPTION

FIG. 1 is a front perspective view of a display screen where the display screen is shown in a closed position.

FIG. 2 is a rear perspective view of the display screen of FIG. 1.

FIG. 3 is a front view of the display screen of FIG. 1.

FIG. 4 is a rear view of the display screen of FIG. 1.

FIG. 5 is a first side view of the display screen of FIG. 1.

FIG. 6 is a second side view of the display screen of FIG. 1.

FIG. 7 is a top view of the display screen of FIG. 1.

FIG. 8 is a bottom view of the display screen of FIG. 1.

FIG. 9 is a front perspective view of the display screen of FIG. 1 attached to a laptop.

FIG. 10 is a front perspective view of the display screen of FIGS. 1-9, shown in an extended configuration.

FIG. 11 is a rear perspective view of the display screen of FIG. 10.

FIG. 12 is a front view of the display screen of FIG. 10.

FIG. 13 is a rear view of the display screen of FIG. 10.

FIG. 14 is a first side view of the display screen of FIG. 10.

FIG. 15 is a second side view of the display screen of FIG. 10.

FIG. 16 is a top view of the display screen of FIG. 10.

FIG. 17 is a bottom view of the display screen of FIG. 10.

FIG. 18 is a front perspective view of the display screen of FIG. 10 attached to a laptop; and,

FIG. 19 is a rear perspective view of the display screen of FIG. 10 attached to a laptop.

The broken lines in FIGS. 9 and 18-19, showing a laptop, represent environment and form no part of the claimed design. The broken lines immediately adjacent to the claimed surfaces represent boundaries. All other broken lines illustrate portions of the display screen which form no part of the claimed design.
